UNITED STATES PATENT OFFICE.

EDWARD N. DICKERSON, OF STOVALL, NORTH CAROLINA.

PROCESS OF MANUFACTURING COMBUSTIBLE GASES.

No. 888,968.

Specification of Letters Patent.

Patented May 26, 1908.

Application filed November 1, 1904. Serial No. 230,925.

To all whom it may concern:

Be it known that I, EDWARD N. DICKERSON, a citizen of the United States, and a resident of Stovall, Granville county, North Carolina, have invented certain new and useful improvements in Processes of Manufacturing Combustible Gases, of which the following is a specification.

This invention relates to an improved process for economically manufacturing combustible gas which may or may not be illuminating in quality.

It is well known that the ordinary operation in manufacturing water gas can only be practically carried out, when coal is used, by the employment of anthracite or similar hot material. It cannot be successfully practiced in cupolas by the use of bituminous coal. On the other hand bituminous coal can be distilled to produce ordinary coal gas leaving a coke which is generally sold in the market for household consumption or similar purposes. Further, in the ordinary process of manufacturing water gas, during the operation known as blowing up, an enormous amount of heat escapes to the atmosphere and is wasted. I propose to utilize the waste heat from a water gas cupola for the coking of bituminous coal while alternately producing water gas from said cupola and filling said cupola with coke, preferably hot, produced in the coal gas bench. The coal and water gas so produced, I further propose to mix and bring together into a common main or holder, whence they may be utilized for heating purposes. I further propose to add to the coal or water gas, if desired, or to both, sufficient illuminant to produce illuminating gas if desired, and I further propose to utilize the waste heat of the cupola in the process of blowing up, after it has aided in the distillation of the coal, in heating an ordinary checker-work which may be subsequently used for heating the air or producing steam to be used in the cupola in the processes of making water gas, and I further propose to aid in the distillation of the coal by causing the hot water gas to pass through or over the same on its way to the holder or mains.

My invention will be readily understood from the accompanying drawings of which,

Figure 1 represents a vertical elevation, partly in section, of one unit of the apparatus; Fig. 2 a front view of a set of cupolas and benches showing the coke transferring carriage.

The operation of one unit of my apparatus is shown in Fig. 1 in which A represents a water gas cupola of any approved construction, and B a coal gas retort, C a heat-absorbing checker-work, D a purifier and scrubber of any suitable construction, and E a transferring carriage for receiving the coke from any one of the coal gas retorts in the bench and transferring it to the desired cupola.

F represents the well known form of cleaning plunger for forcing out the coke, or if desired, leveling the same.

The parts are shown in a diagrammatic way, but will be readily understood by a competent gas engineer.

The cupola A is provided with an air blower and inlet G for blowing up which is shown separate from the blower G' for convenience of illustration, though, manifestly but one blower with suitable connections would be used in practice. The cupola A may, further be provided with an oil pipe H for feeding oil, if desired. It is also provided with a feeding funnel J which is to have suitable valves and a distributor, as shown, if desired. The pipe K connects with the heat absorber, as shown, and may have the branch K' for the supply of steam, if desired. The outlet pipe L is provided with three branches; one L' connecting with the heating chamber surrounding the distilling retort, another L'' entering the chamber of the distilling retort, while the third L''' may connect directly with the mains or place of utilization of the gas or may pass into the scrubber and purifier, as desired. It is manifest that all three branches L', L'' and L''' would not be required unless it is desired to practice the processes for which they are designed. The distilling retort B may be of any ordinary form, such as the coal gas bench generally used, or if desired, the present form of Lowe generator, see U. S. Patent 711,905, for the production of what is known as Lowe anthracite may be employed. In this case the external heating chamber M is of course omitted, but the gas produced may contain a certain amount of nitrogen, as will be presently described. When the chamber M is omitted and replaced by the well known Lowe generator, the retort is heated by the operation of the latter. In case the Lowe style of horizontal retort is employed, the coal may be fed from above in the well known manner, but, otherwise it is fed into the end or ends of the retort.

The carriage E is arranged on rails, as shown, to receive the contents of each of the retorts, as desired, and the pusher or leveler F may also be arranged on rails to operate at 5 each retort at will. An outlet is provided with the retort B by the pipes N, L¹¹ and N' passing to the scrubber and purifier D or directly to the outlet O as desired. The retort B is likewise provided with the inlet T which 10 may be utilized for the introduction of oil. The heating chamber M is provided with the pipe D passing to the bottom of the heat absorber C which, itself is provided with outlet R communicating with the atmosphere. 15 The pipe from the blower G enters the upper part of the checker-work which is also provided with a pipe S through which the steam or oil may be admitted at will.

My process as carried out by me can now 20 be readily understood. The cupola A being assumed to be charged with coke in a state of combustion, and the retort B with a distillable coal or similar material, my operation is as follows: Air either hot or cold, is blown 25 into the base of the cupola in the usual way. This, in case the ordinary coal gas bench is used is caused to pass after combustion through the pipes L' into the heating chamber M thereby heating and distilling the coal 30 in the retort B after passing around the retort B, the hot gases pass through the pipe P through the heat absorber C, and thence escape through the outlet or purge valve R to the atmosphere. Meanwhile, the gases 35 distilled from the coal pass by pipe N either directly to the place of utilization through the pipe O, or through the purifier D to a holder. As soon as the process of blowing up is finished, steam is admitted to the bottom 40 of the cupola through the pipe K either through the inlet K', or it may be generated in the heat absorber C by spraying water through the pipe S. The pipes L', L², L³ and pipe O are respectively provided with valves 45 x', x², x³ and x⁴. Between the pipe N and a nozzle N' leading into the base of the purifier D is a valve x⁵. These valves are opened and closed to permit the gas to pass through the several pipes with which they co-operate 50 into the component elements of the apparatus, or to the main in accordance with the operation desired to be pursued. The water gas produced may pass directly through the outlet O or the purifier D, but preferably 55 passes by the pipe L'' into the coal gas retort where it mingle with the coal gas, and by its heat aids in the distillation of the same. In this case the resulting gas escapes as before, either through the pipe O or the purifier. 60 When the coal has been distilled, the valve x² of the pipe L² is closed, the retort B opened at V, V in the usual way and the coke mechanically or manually caused to fall into the carriage provided with closing valve W, and 65 is then conveyed by the carriage to the cupola

in need of charging and being in a hot condition, its heat can be utilized for the subsequent production of water gas. The carriage is run over the desired funnel and on opening the valve W and the valve in the hopper pipe J, the coke is readily fed into the desired cupola, the retort B being then recharged, and the apparatus prepared to repeat the process. When the water gas from the cupola is to pass directly through the outlet O, 70 the valves x³ and x⁴ are opened, and the valves x¹, x² and x⁵ are closed. If the gas is to pass to the purifier D the valves x¹, x² and x⁴ are closed and valves x³ and x⁵ opened. When the gas is to pass into the retort B, the 75 valves x¹, x³, and x⁴ are closed and valve x² opened. If the heating gas is to pass into the heating chamber M, the valve x¹ is opened and the remaining valves closed, but under certain conditions, or when it is desired to 80 have the gas also pass into the retort at the same time, the valve x² may be opened. It is of course obvious that a separate heat absorber and purifier is not required for each 85 retort; but the pipes from the cupolas and 90 retorts are laterally connected in the usual way so that each may be connected to any other section at will. Of course the drawing is intended to be illustrative, and the pipes and connections would be arranged in practice in the manner well known to all gas engineers and all pipes would be provided with 95 proper valves for controlling heated gases.

In case it is desired to produce fuel gas with some admixture of nitrogen than during 100 the period of the blow off, the gases from the cupola A may be caused to pass through the pipe L² into the coal in the retort B and may be carried away jointly with the gases produced by this distillation, but in this case, 105 the resulting gases will be rendered impure by the nitrogen and products of combustion so mingled with the resulting gases.

What I claim as my invention and desire to secure by Letters Patent is:

A process of producing combined coal and water gas consisting of blasting a bed of fuel to incandescence by means of a fluid and at the same time heating externally by the blast gases a retort containing coal thereby distilling the coal gas and at the same time utilizing the blast gases to heat a checker-work chamber and simultaneously heating the blast fluid passing through said chamber, then producing water gas in the usual way, 120 and then combining the water gas with the distilled coal gas.

In testimony whereof I have signed this specification in the presence of two subscribing witnesses.

EDWARD N. DICKERSON.
